ATTORNEY

UNITED STATES PATENT OFFICE

GEORGE W. JANICIK, OF NEWARK, NEW JERSEY

DOLL'S EYES

Application filed April 10, 1929. Serial No. 353,937.

This invention relates to new and useful improvements in dolls and has more particular reference to moving eyes for dolls.

The invention has for an object the provision of a device of the class mentioned which is of simple durable construction, dependable in use and efficient in action, and which may be manufactured and sold at a reasonable cost.

10 The invention proposes the use of a substantially horizontal rod supported for rotative rocking and supporting at its extremities eye-ball members pivotally arranged for moving laterally in a horizontal plane, the eye-ball members to have rearward projecting lugs connected by a tie rod having a central hook supporting a pendulum, the rotative rocking of the horizontal rod being relative only to forward and rearward tilting of the 15 support rod relative to the pendulum, and lateral movements of the eye-ball members being relative only to lateral tilting of the same support relative to the pendulum.

20 For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

25 Fig. 1 is a front elevational view of a portion of a doll's head constructed according to this invention.

Fig. 2 is a side elevational view thereof.

Fig. 3 is a rear elevational view looking in the direction of the arrows 3—3 of Fig. 2.

Fig. 4 is a horizontal sectional view taken on the line 4—4 of Fig. 2.

Fig. 5 is a rear elevational view of the horizontal rod, the eye-ball members, and the pendulum connection.

Fig. 6 is a side elevational view of Fig. 5.

Fig. 7 is a perspective detail front view of the supporting means for the parts shown in Fig. 5.

Fig. 8 is a vertical sectional view of one of the eye-ball members per se, taken on the line 8—8 of Fig. 5.

Fig. 9 is a perspective view of a spreader tool used for attaching the support shown in Fig. 7 within a doll's head.

Fig. 10 is a fragmentary view of a portion of Fig. 5 constructed according to modified form.

The reference numeral 10 indicates generally a doll's head formed with eye openings 11. Eye-ball members 12 within the doll's head rest against the material of the doll's head surrounding the eye openings.

A substantially horizontal rod 13 with a central offset portion 14 supports at its ends the said eye-ball members 12. Each of the eye-ball members has a pair of spaced rearward projecting lugs 15, and the top lug has an enlarged extension 16. Vertical bolts 17 pass thru apertures in the spaced lugs and thru the ends of the horizontal rod 13 for pivotally holding the eye-ball members. A tie rod 18 engages in apertures formed in the extension 16 and has its ends spread or turned down as indicated by reference numeral 19 for locking it in engaged position. A hook 20 projects from the center of the tie rod and is directed directly over the offset in the horizontal rod 13. A guide angle 21 is attached upon the offset portion 14 and is formed with a guide aperture 22. The stem 23 of a pendulum 24 passes thru the aperture 22 and pivotally connects with the hook 20.

A front plate 25 with a central aperture 26 is formed with forward projecting prongs 27 having end cut-outs 28. These end cut-outs engage the offset portion 14 of the horizontal rod and serve to pivotally hold the rod. The front plate 25 is formed with rearward directed guide lugs 29 slidably supporting a right slide 30 and a left slide 31. The outer ends of these slides are pointed as indicated by numerals 32 and the inner ends are bent rearward as indicated by numeral 33. A tool may be used for spreading the slides and causing them to engage the inner sides of the doll's head 10. This tool consists of a cam element 34 engageable between the rearward bent ends 33, a shank 35 connected with the cam and its front end engageable in the aperture 26, and a turning handle 36. In Fig. 4 the turning tool is shown engaged and in the

operation of spreading the slides for causing their points to engage the doll's head.

In the modified form of the invention illustrated in Fig. 10, the tie rod 18' is shown of several sections joined into a unit by 5 coupler tubes 37. The opposite ends of these coupler tubes have threads of different "hands" so that when the coupler tubes are turned in one direction they shorten the tie rod and when turned in the opposite direction lengthen the tie rod. This arrangement permits an adjustment of the eye-ball members 12 so that the eyes of the doll may be directed directly in front or slightly crossed 10 for simulating a doll having crossed eyes.

In operation of the device, when the doll's head is tilted, the pendulum 24 always tends to maintain a vertical position. In the event that the doll's head is tilted forwards or 20 rearwards, the pendulum will cause the horizontal rod 13 to remain stationary and make it appear that the doll is moving the eye-ball members up and down. In the event that the doll's head is tilted laterally, the pendulum 25 24 will tend to retain its position and the horizontal rod 13 will tilt relative to the pendulum for causing the eye-ball members to move laterally.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In combination with a doll's head having eye openings, a horizontal rod, eye-ball members positioned directly to the rear of the openings and pivotally mounted on the ends of the rod, a tie rod between the eye-ball members for simultaneously moving them, a pendulum pivotally supported on the tie rod, a guide angle attached on the horizontal rod and engaging the stem of the pendulum intermediate of its ends, and means for rotatively supporting the horizontal rod.

2. In combination with a doll's head having eye openings, a horizontal rod, eye-ball members directly to the rear of the openings and pivotally mounted on the ends of the rod, lugs projecting from the eye members and formed with apertures, a tie rod between the eye-ball members for simultaneously moving them, said tie rod having turned down ends for engaging apertures in said lugs projecting from the eye members, a pendulum pivotally supported on the tie rod, a guide angle attached on the rod and 60 engaging the stem of the pendulum inter-

mediate of its ends, and means for rotatively supporting the horizontal rod.

3. In combination with a doll's head having eye openings, a horizontal rod, eye-ball members positioned directly to the rear of the openings and pivotally mounted on the ends of the rod, a tie rod between the eye-ball members for simultaneously moving them, a pendulum pivotally supported on the tie rod, a guide angle attached on the rod and engaging the stem of the pendulum intermediate of its ends, and means for rotatively supporting the horizontal rod, comprising a front plate, guide lugs attached thereon, slides supported by said lugs, the outer ends of said slides having prong points, the inner ends of said slides being formed with inturned portions arranged for spreading.

4. In combination with a doll's head having eye openings, a horizontal rod, eye-ball members at the rear of the openings, outwardly extending lugs fixed to the rear of said eye-ball members and having apertures therein, said eye-ball members pivotally secured to each end of said horizontal rod, a tie rod between the eye-ball members for simultaneously moving them, said tie rod having turned down ends for engaging the apertures in said lugs, a pendulum pivotally supported on the tie rod, a guide angle attached on said horizontal rod and engaging the stem of the pendulum intermediate of its ends, and means for rotatably supporting said horizontal rod.

5. In combination with a doll's head having eye openings, a horizontal rod, semi-spherical eye-ball members at the rear of the openings, a pair of spaced lug members fixed at the rear of each of said eye-ball members and extending rearwardly therefrom, said lug members of each pair positioned one above the other and the upper of greater length than the lower and having two apertures therein, a single aperture in each of said lower lug members and in vertical alignment with the inner aperture in each of said upper lug members, vertical bolt members connecting the upper and lower lug members of each eye-ball member and secured through said vertical aligned apertures, said horizontal rod pivoted at each end to said vertical bolt members, a tie rod between the eye-ball members for simultaneously moving them, said tie rod having turned down ends for engaging the outer apertures of said upper lug members, a pendulum pivotally supported on the tie rod, a guide angle attached on said horizontal rod and engaging the stem of the pendulum intermediate of its ends, and means for rotatably supporting said horizontal rod.

In testimony whereof I have affixed my signature.

GEORGE W. JANICIK.
